[57] CLAIM

The ornamental design for a pouring attachment for
paint cans, as shown and described.

DESCRIPTION

FIG. 1 is a perspective view of a pouring attachment for
paint cans showing my new design;

FIG. 2 is a side-elevational view of the side not seen in
FIG. 1;

FIG. 3 is a top plan view thereof;

FIG. 4 is a rear-elevational view thereof; and

FIG. 5 is a bottom plan view thereof.
